UNITED STATES PATENT OFFICE.

JOSEPH RILEY, OF SABATTUS, MAINE.

MULE STARTER.

Application filed October 7, 1925. Serial No. 60,996.

This invention relates to an attachment for spinning mules of the well known Davis and Furber type, such as illustrated, for example, in the patent to Sullivan No. 5 1,516,354.

In spinning mules of this character, the travelling carriage has the usual to and fro motion and when it is desired to stop the carriage at the rolls, the usual shipper rod 10 is operated which controls well known mechanism for throwing the belt on to an idle pulley whereupon the carriage will stop when it reaches the rolls. When it is desired to start the carriage again, the rod 15 is moved in the reverse direction and the carriage first moves in a short distance and strikes an adjustable pin which releases the belt shifter and permits the belt to move back to the driving pulley so that the carriage moves out again.

If the speed of the carriage is uneven, it may rebound when stopped and if this takes place, the adjustable pin will not be struck and the carriage will fail to start when the 25 shifter rod is again operated. The operator must then start the carriage in one of two ways. He must either push the carriage ahead so that it will contact with the aforesaid pin and start the carriage, which operation requires considerable strength, or he 30 must go to the center of the mule, reach over the carriage and push the pin in by hand, which method is slow and dangerous.

The object of this invention is to provide 35 simple and efficient means for operating the starting mechanism from either side of the mule or at various positions transversely thereof as desired.

In the drawings: 40 Figure 1 is a side elevation of the head portion of a spinning mule of the type illustrated in the patent above cited.

Figure 2 is a detached view in side elevation of the starting mechanism constituting 45 the subject of the invention.

Figure 3 is a front view of a portion of the mule showing the attachment of the structure embodying the invention.

Figure 4 is a detached perspective view 50 of the starter.

Since the particular construction of the mule itself and associated parts forms no part of the present invention, it is believed to be unnecessary to describe the same in detail. There is shown the usual head por-

tion A, a spool stand B, and an adjustable pin C which is operated by the carriage D for the purpose of starting the mechanism. This carriage D carries an adjustable pin E which is adapted to cooperate with the 60 pin C, and, through detent mechanism F, operates the belt shifter G which controls the position of the belt H. While these parts are illustrated as they appear in the usual Davis and Furber mule, such as is 65 shown in patent to Sullivan 1,516,354, of November 18, 1924, nevertheless it is to be understood that the invention is not limited to this particular type of spinning mule, but may be used in other relations.

Clamped to a rod 2 which forms the back support of the spool stand B and held against movement, is an arm 1 to which is pivoted at 3 a link 4 carrying a block 5 through which passes a downturned end of a rod 6 which is held in desired position in said block by means of a set screw 5'. The end of this rod 6 lies just in front of a pin 7 which is carried by the same part as the adjustable screw C. It is, therefore, obvious that a movement of the pin 7 by means of the rod 6 will produce the same operation as if the pin C were moved by the usual traveling carriage.

The rod 6 extends forwardly in a substantially horizontal plane and the end thereof passes through a block 8 to which it is held by a set screw 9. This block is carried by an arm 10 having a sleeve fitting over a rod 12 and fastened thereto by a set screw 90 11. This rod 12 is mounted to rotate in a plurality of links 13, the other ends of which are held in position by the bolts 14 of the front end of the spool stand. A plurality of handles 15 are provided and fastened to 95 the rod 12 in any suitable manner. These handles may be located near either end of the rod 12 or intermediate thereof or both.

It is obvious that after the movement of the carriage has been stopped and it is desired to again start the same, any one of the handles 15 may be operated, thus rocking the rod 12 in its bearings and moving the arm 10 with block 8 which carries the rod 6 to the dotted line position of Figure 2. This causes the downward end of said rod to contact with the pin 7 and move it rearwardly also as indicated in dotted lines in Figure 2, thus producing the same result as if the pin C had been moved rearwardly 110

by movement of the carriage and, therefore, starting the traveling movement of the carriage once more.

It will be obvious that I have provided a very simple and efficient mechanism for starting the traveling movement of the carriage whenever it has been stopped for any reason. It can be readily operated without the exercise of great strength and without any danger whatever. It is also obvious that minor detail changes may be made without in any way departing from the spirit of the invention, which is to be regarded as limited only by the scope of the appended claims.

I claim as my invention:

1. In combination with a spinning mule having means operable to shift the drive member to inoperative position when it is desired to stop the carriage in at the rolls, in which said carriage upon being started thereafter has a further movement toward the rolls, and an element permitting restoration of the drive member to driving position operable through the said further movement of the carriage so that the carriage may be moved out again; means to operate said element in case of failure of operation thereof by the carriage comprising a rod arranged adjacent said element, means journalling said rod on the back support of the spool stand, an operating rod journaled on the spool

stand, and an operative connection between said rods whereby operation of the second mentioned rod will cause said first mentioned rod to shift said element.

2. In combination with a spinning mule having means operable to shift the drive member to inoperative position when it is desired to stop the carriage in at the rolls, in which said carriage upon being started thereafter has a further movement toward the rolls, and an element permitting restoration of the drive member to driving position operable through the said further movement of the carriage so that the carriage may be moved out again; means to operate said element in case of failure of operation thereof by the carriage comprising a rod having a depending portion and a portion extending forwardly therefrom, means journalling said rod on the back support of the spool stand with said depending portion arranged adjacent said element, a rod in crossed relation to said forwardly extending portion journaled on the spool stand forwardly of the back support, and a connection carried by the second rod and pivoted to the forwardly extending portion to cause the depending portion to shift said element through rocking of the second rod.

In testimony whereof, I have hereunto subscribed my name.

JOSEPH RILEY.
